* cited by examiner

Primary Examiner — Cynthia Ramirez(74) Attorney, Agent, or Firm — Ira S. Dorman(57) CLAIM

The ornamental design for a container with a slim handle, as shown and described.

DESCRIPTION

FIG. 1 is a perspective view of a container with a slim handle showing my new design;

FIG. 2 is a front view thereof;

FIG. 3 is a bottom view thereof;

FIG. 4 is a top view thereof;

FIG. 5 is a rear view thereof;

FIG. 6 is a left side view thereof; and,

FIG. 7 is a right side view thereof.

The broken lines in the figures show portions of the container with a slim handle, which form no part of the claimed design.
